DESIGN FOR A PORCH GLIDER OR SIMILAR ARTICLE

Nathan Hurwitz, Cleveland, Ohio

Application June 14, 1938, Serial No. 77,841

Term of patent 7 years

To all whom it may concern:

Be it known that I, Nathan Hurwitz, a citizen of the United States, residing in the city of Cleveland, county of Cuyahoga, and State of Ohio, have invented a new, original, and ornamental Design for a Porch Glider or Similar Article, of which the following is a specification, reference being had to the accompanying drawing, forming a part thereof.

Figure 3 is a side view of an arm of the glider with the drawer open; and

I claim:

The ornamental design for a porch glider or similar article, substantially as shown.

NATHAN HURWITZ.
